Primary Examiner — Jasmine Mlinarcik*Assistant Examiner* — James P McKane(74) *Attorney, Agent, or Firm* — Adibi IP Group, PC; Amir V. Adibi; Andrew C. Palmer(57) **CLAIM**

The ornamental design for overalls, as shown and described.

DESCRIPTION

FIG. 1 is a front perspective view of overalls showing my new design.

FIG. 2 is a front perspective view showing my new design.

FIG. 3 is a right side view thereof.

FIG. 4 is a left side view thereof.

FIG. 5 is a top view thereof.

FIG. 6 is a bottom view thereof.

FIG. 7 is a front view showing the overalls; and,

FIG. 8 is a back view showing the overalls.

The broken lines in FIGS. 2-6 and 8 depict claimed stitching. The cross-hatched lines in the drawings show shading that defines the contours of the overalls and do not reflect a particular surface ornamentation or material.
